UNITED STATES PATENT OFFICE

JOHN F. PETERS, OF PITTSBURGH, PENNSYLVANIA, ASSIGNOR TO WESTINGHOUSE ELECTRIC & MANUFACTURING COMPANY, A CORPORATION OF PENNSYLVANIA

ELECTROSTATIC TRANSFORMER

Application filed October 16, 1925. Serial No. 62,737.

My invention relates to transformers and particularly to electrostatic transformers.

One object of my invention is to provide an electrostatic means for deriving a reduced voltage from an electric transmission line to energize measuring instruments.

Another object of my invention is to provide means for deriving a reduced voltage from an electric transmission line without entailing a substantial loss of electric power.

Another object of my invention is to provide means for deriving a reduced voltage by electrostatic induction.

A further object of my invention is to provide means for deriving a reduced voltage from an electric transmission line that shall be inexpensive to manufacture, accurate in operation and of such simple, sturdy construction that it requires but little attention.

In the prior art, both electromagnetic transformers and resistors have been used to derive a reduced voltage from a transmission line but these methods dissipate current and are, therefore, objectionable.

In my co-pending application Serial No. 680,569, filed December 13, 1923, surge recorders, and assigned to the Westinghouse Electric & Manufacturing Company, I have described an instrument for obtaining a record of the nature of a surge occurring in a high voltage system. The instrument comprises two conducting elements disposed on opposite sides of a sensitized film to subject the film to a potential difference derived from the system and proportional to the voltage developed by the surge.

Inasmuch as the sensitized film or plate will be influenced only by the impression of potential differences in excess of a predetermined value, it is desirable to provide some means for readily obtaining a potential difference that shall be a function of the system voltage or of the voltage developed in the system by a surge in order that the sensitized film or plate may be subjected to such derived voltage.

The derived voltage is normally less than the critical value at which the plate or film will respond so that under normal conditions

no indication is effected on the film or plate. Under abnormal conditions, however, the voltages are sufficiently increased so that the derived voltage is also increased above the critical value at which the film or plate responds to the impressed potential difference.

In order to derive a reduced potential difference which shall be a function of the line voltage in a simple and economical manner, I provide in accordance with my invention, an electrostatic transformer comprising two metal plates, one at line potential and one at zero potential, separated by an air-space. A third metal plate is interposed in the air-space and is charged by the electrostatic field to a potential inversely proportional to the distance separating this plate from the top plate. The potential of this middle plate is used to operate an electric measuring instrument of the type shown in my copending application.

Figure 1 of the accompanying drawings is a front elevational view of an electrostatic transformer embodying my invention.

Fig. 2 is a top view of the transformer shown in Fig. 1.

The electrostatic transformer of my invention comprises, in general, a static shield 1, a ground plate 2, a condenser plate or ring 3 and a switch 4.

The static shield 1 is a horizontally disposed ring supported by a vertically disposed pillar insulator 5 and is charged to the potential of the line through a conductor 6 leading from the line 7. The shield is constructed of iron pipe of such size and diameter that no corona is formed when it is charged to any potential the line may carry.

The insulator pillar 5 is vertically disposed and consists of porcelain members connected by metal pins and is sufficiently high to preclude arcs jumping the air-space separating the static shield 1 from the ground plate 2. A cross member 8 is attached to the top of the insulator pillar which is bolted to the static shield 1 and carries its weight.

The ground plate 2 is a horizontally disposed metal plate at the base of the insulator pillar 5 and is substantially larger, in hori-

zontal dimensions, than the static shield 1. As the name implies, the ground plate 2 rests directly on the ground or is connected to it.

- 5 The condenser plate 3 is a ring similar to the static shield 1, horizontally disposed in the air-space separating the static shield 1 and the ground plate 2 and is so placed that it conforms with the vertically downward 10 projected outlines of the static shield 1. Two insulators 9 and 10 are diametrically attached to the ring 3 and adjustably support it in a position sufficiently near the static shield 1 to give the voltage desired for 15 the manipulation of indicating instruments. The insulator pillar 5 projects through the center of the condenser plate or ring 3, but the air space intervening is sufficiently wide to prevent arcing between the said members. 20 The switch 4 is a controlling switch placed in a circuit between the condenser plate or ring 3 and the indicating instrument 11, that is located within a shelter 12, and provides a means for short-circuiting the condenser 25 plate 3 with the ground when it is desired to handle the indicating instrument 11.

In operation, the line 7 is charged to a high potential which is communicated by the conductor 6 to the static shield 1. An electrostatic field is set up between the static 30 shield 1 and the ground plate 2, which includes the condenser plate 3, inducing an electrostatic potential therein, which, when the switch 4 is open, is transmitted through 35 a circuit comprising the conductor 13 to an indicating instrument 11 disposed in the shelter 12.

When the switch 4 is closed, it connects the ring 3 directly to the ground plate and pre- 40 cludes any danger to one handling the instrument 11.

My invention provides a means for sup- 45 plying a safe potential for potential indicat- ing instruments. The values indicated by the associated instruments, after proper ad- 50 justments, bear a constant relation to the corresponding values of the transmission line, which may easily be ascertained by mul- 55 tiplying the values observed by a predeter- mined constant, or instruments may be cali- brated to give line values directly. The means provided is inexpensive, simple in con- struction, accurate in operation and easily 60 kept in repair. However, my invention is not limited except as set forth in the ap- 65 pended claims.

I claim as my invention:—

1. An electrostatic transformer for deriv- 60 ing a reduced potential from a high-poten- 65 tial circuit, including a ground plate, a con- ducting element spaced therefrom in con- densive relation therewith and electrically 70 connected to said circuit, and means com- 75 prising a plurality of superposed high-pot- 80 tential pin-type insulators supported upon 85 said ground plate for supporting said ele- 90 ment in operative relation with respect to 95 said ground plate.

2. An electrostatic transformer for deriv- 70 ing a reduced potential from a high-poten- 75 tial circuit comprising a ground-plate, a 80 second plate cooperating therewith to con- stitute a high capacity condenser, a column 85 of high-potential insulators supported upon 90 said ground plate and engaging said second 95 plate to support the same in operative posi- 100 tion, a third plate, and means for adjustably 105 supporting said third plate between said ground plate and second plate.

3. A high capacity condenser comprising 100 two spaced elements constituting condenser 105 plates, and means for maintaining said ele- 110 ments in spaced relation comprising a column 115 of high potential pin-type insulators ex- 120 tending therebetween and secured thereto.

4. An electrostatic transformer for deriv- 120 ing a reduced potential from a high-poten- 125 tial circuit including a ground plate, a con- 130 ducting element spaced therefrom in con- 135 densive relation therewith and electrically 140 connected to said circuit, said element being 145 approximately parallel to said ground plate, 150 and means comprising a plurality of super- 155 posed high-potential insulators supported 160 upon said ground plate for supporting said 165 element in operative relation with respect 170 to said ground plate, said insulators being 175 positioned one above the other in a direction 180 perpendicular to the plane of said ground 185 plate.

In testimony whereof, I have hereunto 190 subscribed my name this 8th day of October, 1925.

JOHN F. PETERS.
